CLAIM

The ornamental design for a golf club putter, as shown
and described.

DESCRIPTION

FIG. 1 is a front elevational view of the golf club putter
showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The broken away sections on FIGS. 1-4 and 7 is due to
indeterminate length.

FIG. 1
